Primary Examiner — Justin M Jonaitis*Assistant Examiner* — Samantha K Pollack(74) *Attorney, Agent, or Firm* — ISUS INTELLECTUAL PROPERTY PLLC; Anthony Jason Mirabito(57) **CLAIM**

The ornamental design for a light emitting handpiece, as shown and described.

DESCRIPTION

FIG. 1 is a Top Perspective View of the new design.

FIG. 2 is a Bottom Perspective View of the new design.

FIG. 3 is a Left Side view of the new design.

FIG. 4 is a Right-Side view of the new design.

FIG. 5 is a Top View of the new design.

FIG. 6 is a Bottom View of the new design.

FIG. 7 is a Front View of the new design.

FIG. 8 is a Rear View of the new design; and,

FIG. 9 is a front Perspective View of the new design with a cable and connector in broken lines.

The broken line showing of the cable and connector in FIG. 9 illustrates environmental structure and forms no part of the claimed design. All other broken lines illustrate portions of the light emitting handpiece that form no part of the claimed design.

1 Claim, 8 Drawing Sheets(56)
